(57) **CLAIM**

The ornamental design for an aerosol bottle actuator, as shown and described.

DESCRIPTION

The application relates to an aerosol bottle actuator for use with an aerosol bottle.

FIG. 1 is a perspective view of an aerosol bottle actuator showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines showing an aerosol bottle are for reference and illustrative purposes only and form no part of the claimed design.
